UNITED STATES PATENT OFFICE.

ALLAN S. HUTCHINS, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-DETECTING MECHANISM.

1,349,341.

Specification of Letters Patent.

Patented Aug. 10, 1920.

Application filed August 4, 1919. Serial No. 315,153.

To all whom it may concern:

Be it known that I, ALLAN S. HUTCHINS, a citizen of the United States, residing at Worcester, in the county of Worcester and 5 State of Massachusetts, have invented a new and useful Weft-Detecting Mechanism, of which the following is a specification.

This invention relates to a weft detecting mechanism for use in an automatic weft re- 10 plenishing loom.

The invention further relates more particularly to the double-point type of detecting mechanism, in which a relatively fixed detector and a relatively movable detector 15 are mounted on the same slide or support, and in which indication of weft exhaustion occurs whenever relative movement is permitted between the movable detector and the fixed detector.

20 It is one object of my invention to improve and simplify the construction of the movable detector, at the same time providing a wide range of adjustment, and a simple method of making such adjustment, preferably without the use of tools.

25 In the preferred form, I provide a rotatable detector having a plurality of weft-engaging faces positioned at different radial distances from the axis of the detector, together with means for rendering any selected face of the detector operative to indicate weft exhaustion.

30 My invention further relates to arrangements and combinations of parts which will be hereinafter described and more particularly pointed out in the appended claims.

A preferred form of my invention is shown in the drawings, in which—

Figure 1 is a side elevation of my im- 40 proved detector;

Fig. 2 is a front elevation thereof;

Fig. 3 is an enlarged partial plan view of a portion of the detector slide with the fixed and movable detectors mounted 45 thereon;

Fig. 4 is a sectional elevation taken along the line 4—4 in Fig 3;

Fig. 5 is a plan view of the slide and detector, together with certain associated parts, 50 and

Figs. 6 and 7 are views similar to Fig. 5 but showing the parts in different positions.

Referring to the drawings, I have shown my improved detecting mechanism in the 55 form of a slide 10 having a fixed detector 11

secured thereto or preferably formed integrally therewith. A movable detector 12 is pivoted to the slide 10 and is provided with a plurality of weft-engaging faces 13 formed at different radial distances from 60 the axis of the detector 12. Each face is preferably provided with teeth as indicated in the drawings, and these teeth are preferably formed so that all of the teeth in each face are at the same radial distance from the 65 axis of the detector. This latter feature provides uniform contact with the weft carrier as the detector turns about its axis to indicate weft exhaustion.

The detector 12 may be rotatably mounted 70 on the slide 10 in any convenient manner, and is shown herein as rotatable about a bushing 14 (Fig. 4) set into a recess in the detector 12 and secured to the slide 10 by a screw 15.

75 The slide 10 is slotted at 16 and is slidably secured to a bracket 17 by screws 18 extending through the slot 16. The bracket 17 is fitted to a stand 19 rigidly connected to the loom frame 20. A yielding connection is preferably provided between the bracket 17 and the stand 19, as indicated in Fig. 1, thus permitting displacement of the detecting mechanism by a misplaced shuttle without injury to the detecting mechanism. 80

I have shown my improved detecting mechanism in connection with an actuator 21 of a usual type. This actuator is normally moved freely about a pivot 22 by a plunger 23 which is moved intermittently by 90 driving mechanism not shown. When, however, the free swinging movement of the actuator 21 about the pivot 22 is obstructed, the pivot 22 will be moved to indicate weft exhaustion. Further details of the actuator 95 and its connections may be found in the prior patent to Ryon No. 972,722, issued October 11, 1910.

A controlling rod or wire 24 (Figs. 1 and 5) is normally positioned in the path of the 100 actuator 21. This rod or wire is preferably U-shaped and has a rearwardly extending lower portion supported on ears 25 formed on the side of the slide 10. The upper part of the wire is slidable in a bearing 19 on the 105 stand 19. At its extreme rear end, the lower portion of the U-shaped wire is up-turned sharply to enter one of a series of holes 26 in the movable detector 12. The rearward movement of the wire 24 is limited by a col- 110

lar 27 adjustable thereon, and engaging the bearing 19^a and the wire is yieldingly moved rearward by a light spring 28 connected at one end to a notch or bend in the wire 24 and at the opposite end to a fixed stud 29. A heavier spring 30 connects the forward end of the slide 10 to a fixed stud 31.

The general method of operation of the device is similar to other double-point weft detectors and is clearly indicated in Figs. 10 6 and 7.

In Fig. 6 the device is shown engaged with a weft detector having a sufficient supply of weft thereon. The teeth of the movable detector 12 engage the weft on the weft carrier, which prevents rotation of the detector, and the parts are therefore moved directly forward, or to the left in Fig. 6, withdrawing the wire 24 from the path of the actuator 21. If, however, an insufficient supply of weft is found on the weft carrier, the detector 21 will rotate freely about its axis as indicated in Fig. 7, and the wire 24 will thus remain in its normal position, in which 25 it is engaged by the actuator 21 which is therefore rendered effective to indicate weft exhaustion.

The wire 24 is of sufficient length and flexibility so that it can be readily withdrawn from one of the holes 26 and inserted in a different hole when it is desired to bring a different face of the detector 12 to operative position. By thus changing the adjustment, the relation between the rear end of the fixed detector 11 and the face 35 13 of the movable detector may be varied to correspond to the particular conditions under which the detecting mechanism is operating.

40 It will be seen that the parts are of extremely simple construction and that no close or accurate adjustment is necessary.

Having thus described my invention, it will be evident that changes and modifications can be made therein by those skilled in the art without departing from the spirit and scope of my invention as set forth in the claims. Therefore I do not wish to be otherwise limited to the details herein disclosed, but what I claim is:—

50 1. In a loom, a weft detector having a plurality of weft-engaging faces, means to hold any selected face in operative position, and weft-replenishing mechanism controlled by said detector.

55 2. In a loom, a movable support, a detector fixed to said support, a second detector rotatably mounted on said support, an actuator, and connections through which said 60 rotatable detector is effective to control said actuator in any of a plurality of different

angular operative positions of said detector, and means to attach said connections to said rotatable detector at any one of a plurality of points corresponding to different angularly disposed operative positions of said detector.

3. In a loom, a slide, a detector fixed thereon, a second detector having a plurality of weft-engaging faces and rotatably mounted on said slide, and a member adapted to be connected to said rotatable detector in any angular operative position thereof.

4. In a loom, a movable support, a detector fixed to said support, a second detector rotatably mounted on said support, an actuator, and a member connected to said rotatable detector and controlling said actuator, said detector having a plurality of weft engaging faces, and having provision for connection to said member in any one of several different angular operative positions.

5. In a loom, a movable support, a detector fixed to said support, a second detector rotatably mounted on said support, an actuator, and a member controlling said actuator and positioned by said rotatable detector, said rotatable detector having a plurality of weft-engaging faces positioned at different radial distances from the axis thereof and being effective to position said member with any one of said faces in operative position.

6. In a loom, a movable support, a detector fixed to said support, a second detector rotatably mounted on said support, an actuator, and a U-shaped wire controlling said actuator, said rotatable detector being provided with a plurality of weft-engaging faces and having means to engage one end of said wire with any selected face in operative position.

7. In a loom, a support, a detector fixed thereto, a second detector pivoted thereto and having a plurality of weft-engaging faces positioned at different distances from its axis and having a transverse hole associated with each face, a wire slidably mounted on said support and having one end bent upward and adapted to be inserted in any selected hole, and weft-replenishing mechanism controlled by the longitudinal position of said wire.

8. In a loom, a weft detector pivotally mounted and having a plurality of weft engaging faces, and means to hold a selected face thereof in operative position, each face being substantially concentric with the axis of said detector.

In testimony whereof I have hereunto affixed my signature.

ALLAN S. HUTCHINS.
